(57) CLAIM

I claim the ornamental design for the wallet, as shown and described.

DESCRIPTION

FIG. 1 is a perspective view of the wallet closed;

FIG. 2 is a front view of FIG. 1;

FIG. 3 is a right side view of FIG. 1;

FIG. 4 is a rear view of FIG. 1;

FIG. 5 is a left side view of FIG. 1;

FIG. 6 is a top view of FIG. 1;

FIG. 7 is a bottom view of FIG. 1; and,

FIG. 8 is an environmental front perspective view.

The characteristic feature of the design resides in the overall rectilinear shape of the wallet in combination with two compartment access zippers and a securing loop mounted on the front portion of the wallet. The shape and features shown in broken lines, of the wallet, in the accompanying Figures, are for illustrative purposes only and form no part of the claimed design.
